UNITED STATES PATENT OFFICE.

THOMAS C. BURNS AND FRANK K. HUFFMAN, OF JACKSON, MICHIGAN, ASSIGNEES TO
HAYES WHEEL COMPANY, OF JACKSON, MICHIGAN.

DESIGN FOR A WHEEL-HUB.

56,220.

Specification for Design. Patented Aug. 31, 1920.

Application filed June 19, 1920. Serial No. 390,262. Term of patent 14 years.

To all whom it may concern:

Be it known that we, THOMAS C. BURNS and FRANK K. HUFFMAN, citizens of the United States, and residents of the city and county of Jackson, State of Michigan, (whose post-office addresses are care of the Hayes Wheel Company, Jackson, Michigan, respectively,) have invented a new, original, and ornamental Design for Wheel-Hubs, of which the following is a specification, reference being had to the accompanying drawing, forming a part thereof, in which—

Figure I is a side view of a wheel hub showing our new design, and

Fig. II is an end view of a wheel hub showing the same.

We claim:

The ornamental design for a wheel hub as shown.

In witness whereof, we have hereunto set our hands and seals in the presence of two witnesses.
